UNITED STATES PATENT OFFICE.

MICHAEL DENIS, OF PARADISE, MONTANA.

RAILWAY-RAIL.

1,095,460.

Specification of Letters Patent.

Patented May 5, 1914.

Application filed November 29, 1913. Serial No. 803,731.

To all whom it may concern:

Be it known that I, MICHAEL DENIS, a citizen of the United States, residing at Paradise, in the county of Sanders and State of Montana, have invented certain new and useful Improvements in Railway-Rails, of which the following is a specification.

This invention relates to improvements in railway rails which are made in sections—viz., a tread section and a base section, the same being separate and adapted to be assembled to form a complete rail.

It is the object of the invention to provide a strong and durable rail of this kind, and one having its sections so shaped that they can be easily and cheaply manufactured.

A further object of the invention is to provide a novel and improved joint for the sections.

20 The herein stated objects are attained by a combination and arrangement of parts to be hereinafter described and claimed, reference being had to the accompanying drawing, in which—

25 Figure 1 is a perspective view showing the parts constituting the rail assembled; Fig. 2 is an elevation of the rail showing the manner in which the parts break joint; Fig. 3 is a vertical cross-section on the line 3—3 of Fig. 1, and Figs. 4, 5 and 6 are perspective views of the parts separated.

As shown in the drawing, the rail comprises a tread section consisting of a head 10 from the bottom of which depend spaced 35 parallel flanges 11, which latter extend throughout the entire length of the section. The flanges are thickest at the top where they join the head, and they taper toward their lower ends. The rail also has a base 40 section comprising base flanges 12 and a central upstanding web 13 extending throughout the entire length of said section. The base flanges are shaped like the base flanges of an ordinary rail.

45 The two sections herein described are assembled by slipping the tread section over the web 13, the latter fitting between the flanges 11. It will be noted that the flanges 11 terminate a short distance from the base 50 flanges 12, and that the web 13 extends up to the head 10 and fits squarely against the bottom thereof, between the flanges 11. The contiguous portions of the web and the flanges are smooth, and the former fits 55 snugly between the latter. The tread sec-

tion is supported solely by the web 13, on top of which latter the head 10 rests. This gives the tread section a firm support, and a strong and rigid structure is produced.

The sections are assembled in break-joint order, and provided with fish-plates 14 at the joints. The fish-plates are located at the joints between adjacent tread sections, and also at the joints between adjacent base sections, as clearly shown in Fig. 2. The fish-plates are secured by bolts 15 as usual, and the bolt holes in the parts through which said bolts pass are elongated to allow expansion and contraction of the rail.

The top of the fish-plate 14 fits snugly 70 under the head 10, and the base 16 of the fish-plate seats on top of the base flanges 12. The web of the fish-plate has an inside rib 17 at the base which fits snugly in the angle between the web 13 and the base flange 12, 75 between the latter and the bottom of the flange 11. Thus, the joint is securely braced, and made firm and rigid.

By giving the parts the shape herein described they can be easily manufactured, it 80 being possible to roll them in the same manner ordinary rails are rolled. The sections can be readily assembled, and if the tread section gets worn down on one side, it can be removed and replaced in reverse position; or if worn on both sides it can be removed 85 and renewed. Thus, it is not necessary to remove the entire rail, and a considerable saving in the maintenance costs is effected. The base section ordinarily, is not subject to 90 wear, and need therefore not be removed. The track can therefore be repaired at practically one-half the cost of repairs to a track composed of the ordinary one-piece rails. In the event of either section breaking, the 95 rail will remain in position until repaired, whereas a one-piece rail would spread and loom up on the ends.

The structure makes what is practically a solid rail, and one which is strong and durable, and which can be used on curves, as well as on a straight track. The rail can also be connected to any standard one-piece rail, and it can be cheaply manufactured.

I claim:

The combination of a sectional railway rail composed of a tread and a base section, the tread section comprising a head having depending, spaced parallel flanges, and the base section comprising a base having an up- 110

standing web fitting between the flanges of the tread section, the lower extremities of said flanges being spaced from the base, and fish-plates over the joints of the respective sections, said fish-plates fitting at the top against the bottom of the head of the tread section, and having a rib at the bottom fitting in the angle between the web and the base, between the latter and the bottom of the aforesaid flanges. 10
In testimony whereof I affix my signature in presence of two witnesses.

MICHAEL DENIS.
